UNITED STATES PATENT OFFICE.

WILLIAM L. MILLER, OF MADISON, WISCONSIN, ASSIGNOR TO GISHOLT MACHINE COMPANY, OF MADISON, WISCONSIN, A CORPORATION OF WISCONSIN.

AUTOMATIC CROSS-SLIDE FEED-TRIP FOR LATHES.

1,072,484.

Specification of Letters Patent.

Patented Sept. 9, 1913.

Application filed March 28, 1913. Serial No. 757,386.

To all whom it may concern:

Be it known that I, WILLIAM L. MILLER, a citizen of the United States, residing at Madison, in the county of Dane and State of Wisconsin, have invented certain new and useful Improvements in Automatic Cross-Slide Feed-Trips for Lathes, of which the following is a specification.

This invention relates to improvements in lathes, and has reference more particularly to a new and improved mechanism for automatically arresting the feed movement of the cross-slide.

The main object of the invention is to provide a mechanism that will permit a finer adjustment of the automatic feed-trip mechanism than has heretofore been possible, and by which successive feed-arresting movements can be effected in very close succession corresponding to very short movements of the cross-slide tool.

With this object in view, my invention comprehends, as its chief essential feature, the provision of a feed-trip disk that is geared to rotate in a fixed ratio to the cross-feed screw, and carrying on its periphery one or more trip-blocks coöperating with a lever through which the driving mechanism of the cross-feed screw may be disconnected; the rate of movement of the periphery of said feed-trip disk bearing such a relation to the rate of movement of the cross-slide as to enable successive tripping movements to occur under successive movements of the cross-slide of much shorter extent than is possible where the feed-trip mechanism is attached directly to the cross-slide itself.

The subject matter of my present invention, its mode of operation, and the advantages which inhere therein may be readily understood when considered in connection with the accompanying drawings, in which I have illustrated my invention as applied to an ordinary engine lathe; and referring thereto,—

Figure 1 is a side elevation of the head-stock end of a lathe, showing a cross-slide carriage and cross-slide, with my improved cross-slide trip applied thereto. Fig. 2 is an enlarged vertical section on line 2—2 of Fig. 1. Fig. 3 is an enlarged vertical section on the line 3—3 of Fig. 1. Fig. 4 is a detail of one of the tripping dogs. Fig. 5 is a fragmentary top plan detail view, partly in horizontal section on line 5—5 of

Fig. 1, of a catch mechanism between the trip-arm and clutch-lever. Fig. 6 is a top plan view of the cross-slide reversing gear.

Referring to the drawings, 10 may designate as an entirety a portion of the lathe bed, in bearings 11 and 12 of which is mounted the usual spindle 13 having stepped pulley 14, chuck-head 15, and chuck-jaws 16. On ways 17 of the lathe bed is mounted the usual cross-slide carriage 18 which, in turn, supports the cross-slide 19; this latter in turn carrying the usual tool-carrier 20 and tool-clamp or holder 21, all as usual in lathes of this type.

The cross-slide 19 is reciprocated transversely of the ways 17 by the usual screw 22 suitably journaled in the cross-slide carriage 18 and engaging a nut 23 confined between depending lugs of the cross-slide through which the screw passes, as usual. The screw 22 is driven in either direction from the lathe spindle 13 through a train of gears comprising gear 24 on the spindle, intermediate gear 25, gear 26 on a cross-shaft 27, a change-gear 28 on the remote end of the latter meshing with and driving a change-gear 29 fast on another cross-shaft 30, a bevel-gear 31 on the other end of shaft 30, co-operating bevel-gears 32 and 32' loose on a counter-shaft 33, a double clutch 33' splined on shaft 33 between bevel-gears 32 and 32', gear 34 loosely mounted on the other end of shaft 33 and made fast with the latter through a clutch 35 splined to shaft 33, spur-gear 36 loose on a way-shaft 37 and connected to the latter through a manually-controlled clutch 38 having an operating handle 39, bevel-gear 40 on the other end of shaft 37, coöperating bevel-gear 41 on a stub-shaft 42, gear 43 on the outer end of shaft 42, and coöperating pinion 44 on the adjacent end of the screw-shaft 22.

Fast on the shaft 37 is a worm 45, that engages and drives a worm-wheel 46 (Fig. 2) on the inner end of a sleeve 47 loosely mounted on a bonnet 48 attached to the side wall of the bed 10; and on the other end of the sleeve 47 is a disk 48, the circumference of which is formed with a dove-tail groove, as shown, thereby forming a pair of rims 49 and 50 to which are secured trip-blocks 51 and 52, respectively, each of said trip-blocks having a tapered or pointed outer end. The ratio of gearing between the worm-drive of the disk 48 and the cross-feed screw 22 is 110

preferably such that the disk 48 makes one complete revolution on its axis during one complete in or out travel of the cross-slide, and the circumference of the disk is greater 5 in point of length than the extent of in or out travel of the cross-slide, thus making it possible to trip the cross-slide at shorter intervals than the width of the trip-blocks 51 and 52. For instance, if the circumference 10 of the disk is equal to twice the length of travel of the cross-slide, then the cross-slide can be tripped in one-half the width of one of the trip-blocks. The trip-blocks on one rim or flange of the disk are used for 15 tripping the cross-slide when it is traveling in toward the center of the lathe spindle; while the trip-blocks on the other rim or flange of the disk are used for tripping the cross-slide when it is traveling out or away 20 from the center of the spindle.

Secured to the side wall of the lathe bed above and transversely of the shaft 37 is a stud 53, on the outer end of which is pivoted a trip-arm 54. The free end of the arm 54 25 directly overlies the periphery of the disk 48 and has pivoted therein a pair of dogs 55 and 56, one of which is shown in detail in Fig. 4. These dogs have inclined or tapered lower ends, as shown, and are normally 30 maintained in vertical position by springs 57, and, further, are provided each with one square upper corner 58 and a rounded upper corner 59 so that they will yield when engaged by the trip-blocks 51 and 52 in one 35 direction, but are rigid and effect the raising of the arm 54 when engaged by the trip-blocks 51 and 52 in the opposite direction; it being understood that the two dogs 55 and 56 are so mounted as to yield in opposite 40 directions relatively to each other. The arm 54 is normally drawn downwardly by a spring 60 to a position in which the dogs 55 and 56 lie in the paths of movement of their coöperating trip-blocks 51 and 52, respectively. 45

Pivoted at 61 is a clutch-lever, the lower forked end 62 of which engages the clutch 35, while its upper arm 63 extends upwardly and is slightly offset so as to cross the trip-arm 54 behind the latter, as clearly shown 50 in Fig. 2. On the inner side of the trip-arm 54 is a laterally projecting catch 64 that normally engages a notch formed centrally of the upper edge of a keeper 65 formed 55 on the adjacent side of the lever-arm 63; the keeper 65 being of such width that the catch 64, when disengaged from the notch, will still ride upon the upper edge of the keeper 65. A spring 66 connected to the 60 lower arm 62 of the lever normally urges the lever in a direction to separate the clutch member 35 from the clutch-hub of the transmission gear 34. A lever 67 (Fig. 1) affords manual operation of the direction-reversing 65 clutch 33.

In the operation of the mechanism, assuming that the parts are in the relative positions, shown in Fig. 1, with both of the clutches 35 and 38 engaged, the trip-disk 48 is turning in the direction indicated by the arrow at a peripheral speed greater than the speed of travel of the cross-slide. Trip-blocks 52 are secured to the periphery of the disk at such points as it may be desired to interrupt the inward feed of the cross-slide; while trip-blocks 51 may be likewise secured to the periphery of the disk 48 at such points as it may be desired to interrupt the outward feed or travel of the cross-slide. When one of the trip-blocks 52 70 engages the dog 56, the trip-arm 54 is raised, disengaging the catch 64 from the notch of the keeper 65, whereupon the spring 66 at once acts to retract the clutch-member 35, thereby arresting the further 75 inward travel of the cross-slide until the parts are restored to normal position by manual manipulation of the lever-arm 63, whereupon the feeding movement is resumed. If, during this action, one or more 80 of the trip-blocks 51 engages the dog 55, the latter is merely tripped idly without affecting the trip-arm 54. The same operation takes place when the cross-slide is traveling in the reverse direction and the tripping disk 48 is, consequently, turning in the opposite direction. In such case the trip-blocks 51 and dogs 55 are the operative members to raise the trip-arm 54 and interrupt the feed, while the trip-blocks 52 and 85 dogs 56 merely engage each other idly. 90

My invention by employing a disk geared to turn in a fixed ratio to the turning movement of the cross-slide screw, with trip-blocks applied to the circumference thereof, 95 enables the operator to secure a much finer adjustment of the cross-slide tripping action than has heretofore been possible; and it will be obvious that the greater the diameter of the disk 48 (under a fixed ratio of the 100 worm-drive relatively to the cross-slide travel), the finer will be the feed-tripping action obtainable. 105

I claim—

1. In a cross-slide tripping mechanism for lathes, the combination of a cross-slide, mechanism, including a clutch, for actuating said cross-slide, means constantly urging said clutch into disengaged position, a disk geared to turn in a fixed ratio to the movement of said cross-slide, trip-blocks mounted on said disk, and means actuated by said trip-blocks controlling said clutch-disengaging means. 115
2. In a cross-slide tripping mechanism for lathes, the combination of a cross-slide, mechanism, including a clutch, for actuating said cross-slide, means constantly urging said clutch into disengaged position, a disk 120 geared to turn in a fixed ratio to the move- 125

ment of said cross-slide, trip-blocks mounted on said disk, a clutch-shifting lever, a movable member carrying a dog disposed in the path of said trip-blocks, and means actuated by said movable member controlling the movement of said lever in a direction to effect disengagement of said clutch.

3. In a cross-slide tripping mechanism for lathes, the combination of a cross-slide, mechanism, including a clutch, for actuating said cross-slide, means constantly urging said clutch into disengaged position, a disk geared to turn in a fixed ratio to the movement of said cross-slide, trip-blocks adjustably mounted on the periphery of said disk, a clutch-shifting lever, a movable member carrying a dog disposed in the path of said trip-blocks, said dog being mounted to yield laterally in one direction only, and means actuated by said movable member controlling the movement of said clutch-shifting lever in a direction to effect disengagement of said clutch.

4. In a cross-slide tripping mechanism for lathes, the combination of a cross-slide, mechanism, including a clutch, for actuating said cross-slide, means constantly urging said clutch into disengaged position, a disk geared to turn in a fixed ratio to the movement of said cross-slide, trip-blocks adjustably mounted on the periphery of said disk, a clutch-shifting lever, a pivoted trip-arm, a dog pivoted in the free end of said trip-arm and normally in the path of said trip-blocks, said dog yielding laterally under contact of said trip-blocks when moving in one direction but rigid under such contact when said trip-blocks are moving in the opposite direction, and means actuated by said trip-arm controlling the movement of said clutch-shifting lever in a direction to effect disengagement of said clutch.

5. In a cross-slide tripping mechanism for lathes, the combination of a cross-slide, mechanism, including a clutch, for actuating said cross-slide in both its in and out move-

ments, means constantly urging said clutch into disengaged position, a disk geared to said cross-slide actuating mechanism to turn in a fixed ratio to the movement of said cross-slide, two sets of trip-blocks mounted on said disk, and means actuated by the trip-blocks of each of said sets controlling said clutch-disengaging means.

6. In a cross-slide tripping mechanism for lathes, the combination of a cross-slide, mechanism, including a clutch, for actuating said cross-slide, means constantly urging said clutch into disengaged position, a disk geared to said cross-slide actuating mechanism to turn in a fixed ratio to the movement of said cross-slide, two sets of trip-blocks mounted on said disk, a clutch-shifting lever, a movable member carrying a pair of dogs disposed respectively in the paths of said sets of trip-blocks, one of said dogs being in operative relation to its co-operating set of trip-blocks under a turning movement of said disk in one direction and the other of said dogs being in operative relation to its co-operating set of trip-blocks under a turning movement of said disk in the opposite direction, and means actuated by said movable member controlling the movement of said clutch-shifting lever in a direction to effect disengagement of said clutch.

7. In a cross-slide tripping mechanism for lathes, the combination of a cross-slide, mechanism, including a clutch, for actuating said cross-slide, a disk geared to turn in a fixed ratio to the movement of said cross-slide, trip-blocks mounted on said disk, a clutch-shifting lever, a spring actuating said lever in one direction, a catch normally holding said lever against the action of said spring, and means actuated by said trip-blocks for releasing said catch.

WILLIAM L. MILLER.
